UNITED STATES PATENT OFFICE.

ELBERT A. HAMMETT, OF KANSAS CITY, MISSOURI.

METHOD OF LOCATING KNOCKS IN EXPLOSIVE ENGINES.

Application filed March 10, 1919. Serial No. 281,894.

To all whom it may concern:

Be it known that I, ELBERT A. HAMMETT, a citizen of the United States, residing at Kansas City, in the county of Jackson and 5 State of Missouri, have invented certain new and useful Improvements in Methods of Locating Knock in Explosive Engines; and I do declare the following to be a full, clear, and exact description of the invention, such 10 as will enable others skilled in the art to which it appertains to make and use the same, reference being had to the accompanying drawings, and to the letters and figures of reference marked thereon, which form a 15 part of this specification.

This invention relates to a method of locating "knocks" in explosive engines and the like.

So-called "knocks" that is, loose parts in 20 the engines, are indicated by an apparent pounding or jerky motions at the ends of the strokes of the engine piston, and the objections are well known to those skilled in the explosive engine art.

25 The "knocks" are generally caused by loose connecting rods, loose wrist pins, looseness in the main bearings or piston slap, but the particular seat of trouble is difficult to determine from the sound of the engine.

30 This is due in part to the fact that during the operation of the engine there is considerable diverting noise, due to the clacking of valves, contact of the cams, explosion in cylinders other than the one in which the 35 difficulty arises and the noise caused by the operating parts.

I have found that the difficulty may be 40 readily located by stopping the engine and then turning the piston crank to practically dead center on the compression stroke just prior to firing, so that both the inlet valve and the exhaust valve will be seated, and then varying the pressure in the compression cylinder from an external source 45 so that any looseness in the piston, piston rings, wrist pins, main bearings, connecting rods, or leakage in the valves may be determined in any particular cylinder, it being necessary to vary the pressure in each 50 cylinder separately to test the correctness of the adjustments or determine their deficiencies, but this can be done while the engine is at rest so there may be no diverting noises and that any test may be locally 55 made for a particular cylinder, as will be presently explained.

The figure in the drawing is a fragmentary perspective view of a known type of engine to which a device is attached for carrying out my method. 60

Referring now to the drawings by numerals of reference—

1 designates engine case to which is connected the usual cylinder 2 provided with a piston 3, and connecting rod 4, wrist pin 5, 65 crank shaft 6, inlet valve 7, exhaust valve 8, and such other appurtenances as are common to gas engines. The cylinder head 9 is provided with the usual spark plug opening 10 into which may be screwed a nipple 11 of 70 a pump cylinder 12, provided with a piston 13 operated by a pump rod 14.

When it is desired to locate the cause of a "knock" the operator removes the spark plug and screws the nipple 11 of the pump 75 12 into the opening 10 as shown, whereupon the piston 13 may be operated to vary the pressure in the combustion chamber 15 by creating a vacuum or by introducing pressure, it being desirable, as heretofore explained, to first "crank" the piston to a dead center position or to the end of its compression stroke so that both valves 7 and 8 are seated. If the piston 13 is pushed toward the cylinder head and there is an escape of air passing the piston in the crank case or to the outside atmosphere, it will be apparent that the piston rings are not packing as efficiently as intended. If the escape of air is at either of the valve seats, it will 80 90 be apparent that the valve seats or the valve need grinding. If there is any loose movement of the piston there will be evidence of looseness in the connecting rod and wrist pin. An upward pull on the piston 13 may 95 cause a loose movement of the piston, may indicate leakage through the piston ring or may indicate looseness in the bearings or wrist pin.

If the downward stroke of the piston is 100 strongly opposed by the compression in the compression chamber, and if the upward movement of the piston is seriously opposed by the suction therein, there is evidence that that particular cylinder needs 105 no attention as the rings and valves are tight and that no movement exists for the rings, the piston or the wrist pins. The investigator then unscrews the nipple, inserts the spark plug and proceeds to the next 110 cylinder and repeats the operation until the "knock" is located.

The advantage of the above method will be apparent when it is considered that a "knock" may only occur in one cylinder of a six, eight or twelve cylinder engine, and that by locating the trouble only that part of the engine may be removed which is required to gain access to the part affected, and considerable saving of time will result with almost positive assurance that the trouble has been properly diagnosed and corrected.

Having described my invention, what I claim as new therein and desire to secure by Letters-Patent is:—

15 1. The method of locating "knocks" in explosive engines, which consists in alternately raising and lowering the pressure in the explosion chamber of the engine while the intake valve and exhaust valve are seated.

2. The method of locating "knocks" in explosive engines, which consists in raising the pressure in the explosion chamber of the engine by pumping air into the same from an external source, while the intake and exhaust valves are closed and the piston is substantially on dead center.

3. The method of locating "knocks" in explosive engines, which consists in connecting a pump to the explosion cylinder and operating the pump to vary the pressure in the cylinder.

4. A method of locating a loose piston connection in one cylinder of an internal combustion engine, the method consisting in alternately raising and lowering the pressure of a fluid within the cylinder, while the engine is at rest.

In testimony whereof I affix my signature.
ELBERT A. HAMMETT.
